DESIGN FOR A SHOE OR SIMILAR ARTICLE

Robert E. Frederick, New York, N. Y.

Application April 12, 1949, Serial No. 1,929

Term of patent 7 years

(Cl. D7—7)

To all whom it may concern:

Be it known that I, Robert E. Frederick, a citizen of the United States of America, residing in New York, county of New York, and State of New York, have invented a new, original, and ornamental Design for a Shoe or Similar Article, of which the following is a specification, reference being had to the accompanying drawing, forming part thereof.

The figure on the drawing is a perspective view of a shoe or similar article showing my new design, the opposite side presenting substantially the same appearance as that shown.

The dominant feature of my design resides in the portions shown in solid lines.

I claim:

The ornamental design for a shoe or similar article, substantially as shown and described.

ROBERT E. FREDERICK.
